UNITED STATES PATENT OFFICE.

CHARLES H. BIRCH, OF CHICAGO, ILLINOIS.

FLUID MOTOR, PUMP, AND THE LIKE.

1,158,621.

Specification of Letters Patent.

Patented Nov. 2, 1915.

Application filed September 6, 1910. Serial No. 580,477.

To all whom it may concern:

Be it known that I, CHARLES H. BIRCH, a citizen of the United States, residing at Chicago, in the county of Cook and State of Illinois, have invented certain new and useful Improvements in Fluid Motors, Pumps, and the like.

My invention relates to motors, pumps or the like wherein a plurality of blades or impellers are arranged to rotate in a suitably formed cylinder and coöperate with the walls of the cylinder to move or be moved by a fluid passing through the cylinder.

The object of my invention is to provide a simple, efficient and durable device of the kind described wherein substantially all of the advantages of both a reciprocating and a rotary device are secured with few or none of the disadvantages of either.

To this end my invention consists in the novel construction, arrangement and combination of parts herein shown and described and more particularly pointed out in the claims.

In the accompanying drawings wherein like or similar reference characters indicate like or corresponding parts: Figure 1 is a side elevation of my device with one end shown in section, taken substantially on line 1—1 of Fig. 2. Fig. 2 is a section taken substantially on line 2—2 of Fig. 1. Fig. 3, is a side elevation of one of the blades of my device shown in its normal relation to the blade driving mechanism upon the casing.

Fig. 4 is an end elevation of the parts shown in Fig. 3. Figs. 5, 6 and 14 are details of the mechanism for preventing leakage between the blades and the blade driving mechanism upon the casing. Figs. 7 and 8 are side and edge elevations respectively of the blade driving mechanism upon the shaft.

Figs. 9 and 10 are enlarged details of the mechanism shown in Figs. 7 and 8. Figs. 11 and 12 are details of parts of the mechanism shown in Figs. 7 and 8. Fig. 13 is a view similar to Fig. 2 but showing the parts in a slightly different position.

In the drawings for the purpose of illustration my invention is shown embodied in the construction of a pump in which 1 is a cylindrical casing provided with an inlet

opening 2 and an outlet opening 3 arranged in any desired relation to each other. The ends of the casing 1 are each preferably slightly enlarged as at 6—6 and provided with cover plates 5—5' respectively rigidly secured to the casing and each provided with a central transverse bearing 40.

A shaft 4 is rotatably mounted in, and extends between the bearings 40 with one end 41 projecting sufficiently beyond its bearing to receive a pulley, gear, or other suitable driving means for rotating the shaft. A pair of drivers 18—18 are mounted upon the shaft 4, one positioned in each enlarged part 6 of the cylinder. Each driver is rigidly secured upon the shaft 4 with a part 7 at its periphery arranged to bear against the shoulder 42 at the junction between the main or central portion of the cylinder and the enlarged part 6.

In the form shown three blades or impellers 8—8¹—8² are provided upon the shaft 4, each independently rotatable upon the shaft and suitably formed to fill the space between the drivers 18 and extend from the shaft 4 to the cylinder wall. The parts co-operating with the shaft and cylinder wall are provided with resilient packing or other convenient means arranged to prevent leakage at the margins of the blades. The several blades may be rotatably attached to the shaft 4 in any desired manner, as shown, each blade is provided with one or more bearings or rings 43 adapted to fit the shaft and in the preferred form shown a series of rollers 35 are positioned between the shaft and the ring to serve as a roller bearing and eliminate friction as far as possible. Suitable means are also provided to prevent leakage between the several rings. In the form shown a pair of plates or washers 27—27 are provided at the ends of each ring 43 and a resilient washer 28 formed of leather or other suitable material is positioned between them to hold the plates 27 in contact with their respective rings and prevent leakage at the margins of the plates.

Suitable means are also provided at the outer edge of each blade to form a fluid tight joint between the blade and the cylinder wall. As shown a recess 44 is provided in

the forward edge of each blade and a strip of suitable material 29 is positioned in the recess 44 adapted to snugly fit against and coöperate with the cylinder wall. As shown 5 suitable springs 45 or other convenient resilient means are positioned in the recess at the back of each strip 29 arranged to press against the strip and hold the same in contact with the wall and studs, screws or 10 equivalent means 46—46 are provided at suitable intervals extending through the strip into the blade to hold the strip 29 in position.

Any suitable means may be provided to 15 rotate the blades 8 and control their position. As shown each blade is provided at its extremities with a suitable notch or recess 47 formed in the rear wall of the blade and a pair of hooks or latches 19 are pivotally 20 mounted upon the driver 18 with a part 48 adapted to project beyond the face of the driver and in position to enter the recess 47 in each blade, so that as the shaft is rotated the hooks 19 upon the drivers will successively 25 engage certain of the blades and lock the same to the shaft.

Suitable means are also provided to 30 retract the hooks 19 to disengage the same from the blades and to control the position 35 of the hook. As shown each hook 19 is pivotally mounted upon a stud or projection 20 with a rectangular opening 24 intermediate the ends of the hooks. A pin 22 is rigidly mounted upon the driver and extends 35 through the opening 24 and a cam 21 is rotatably mounted upon the pin 22 adapted to coöperate with the walls of the opening to control the position of the hook and move the same into or out of engaging position.

40 Any desired means may be provided to operate the cam 21. In the preferred construction shown, an arm 49 is formed integrally with or rigidly secured to the cam 21 and projects slightly beyond the periphery of 45 the driver 18 at each side of the center line of the cam. A pair of stops or pins 25—26 are provided upon the inner wall of the enlarged part 6 of the cylinder, each arranged in the path of one end of the arm so that as 50 the driver 18 is rotated the opposite ends of the arm 49 will be successively engaged by the stops 25 and 26 and partially rotated in opposite directions at each engagement thereby moving the cam 21 and alternately 55 retracting and projecting the part 48 upon the hook 19. The inlet opening 2 and outlet opening 3 are arranged in close proximity to each other and in direct communication with the interior of the cylinder 1, a portion of 60 the cylinder 50 being positioned between them. The several parts are so proportioned and arranged that when each blade engaged by the hooks 19 has sufficiently engaged the outlet side of the part 50 to prevent leakage

between the inlet and the outlet openings, 65 the hooks 19 engaging that particular blade are retracted and held in their retracted position until they have passed the blade, when 70 they are again projected into position to engage the next preceding blade in the cylinder, which has been advanced into a suitable position to be reengaged by the hooks 19 and is still preferably in position to coöperate with the inlet side of the part 50 to prevent 75 communication between the inlet and outlet openings as shown in Fig. 13.

Any suitable means may be provided to engage the blades as soon as they are released from the drivers 18 and control their position until they are reengaged by the 80 drivers. In the form shown the cylinder 1 is provided with an annular recess or enlargement 51 intermediate its ends and a transverse socket or shell 52 is provided in the casing at the junction of one side of said recess 85 with the main wall of the cylinder, one end of the socket 52 is provided with a suitable bearing 53. A sleeve or collar 54 or other suitable means adapted to serve as a bearing is provided in the opposite end of the socket 90 arranged to coöperate with the bearing 53 to rotatably support a shaft 10 in position. A worm-wheel 55 is rigidly mounted upon the shaft 10 with a portion of its periphery extending into the recess 51. Each blade 8 is 95 provided with a portion extending into the recess 51 and with means adapted to coöperate with the worm-wheel 55 to control the position and movements of the blade when released from the drivers 18. In the 100 form shown, a bearing 56 is provided upon each blade and a roller 9 is positioned in the bearing with one end 57 projecting and arranged to coöperate with the worm-wheel.

In the form shown a plate 30 is also adjustably secured to each blade partially inclosing the end 57 of the roller 9 and adapted to coöperate with the roller and worm-wheel 55 to prevent leakage past the blade at this point, yet permit the side of the roller to 110 engage the threads upon the worm-wheel to reduce the frictional engagement with the worm-wheel as far as possible.

Any suitable means may be provided for 115 rotating the shaft 10. In the form shown suitable bearings 58—59 are provided upon the casing and a shaft 13 is rotatably mounted in said bearings and provided with a spur gear 14 at one end. A spur gear 16 is also provided upon the shaft 4 and an intermediate gear 15 is mounted upon a suitable stud 17 rigidly secured to the head 5 and adapted to mesh with and transmit power from the gear 16 to the gear 14. A beveled gear 12 is also provided upon the 120 shaft 13 and arranged to mesh with a similar gear 11 upon the shaft 10, the several parts are so proportioned and timed that the 125

worm-wheel 55 engages the roller 9 of a blade just at the instant the hooks 19 release the blade. The blade is then moved by the worm-wheel 55 into a position to be engaged by the next pair of hooks 19 as soon as the next following blade is brought into release position and each blade is moved forward from the release to the reengaging position by the worm 55 so that the released blade 10 and the next succeeding pair of hooks 19 arrive at the reengaging position substantially simultaneously and the blade is wholly released from the worm at the instant the hooks 19 engage it.

15 In operation the shaft 4 is rotated in the direction indicated in Fig. 2. The hooks 19 are engaged with two blades 8 and 8² which are thereby locked to the shaft 4 and move at a substantially uniform velocity when the 20 shaft is rotated. The blade 8' is engaged by the worm and is substantially stationary, the movement being merely sufficient to carry the blade 8' into position to be engaged by the hooks 19 when they reach the engaging 25 position after bringing the blade 8 into the position shown in Fig. 13. At this point the blade 8 is released from the drivers 18 and engaged by the worm 55 and as soon as the hooks 19 reach a position to engage the blade 30 8' the same is released from the worm 55 and moved forward by the drivers with the blade 8² until the blade 8² arrives at the release position, the blade 8 having in the mean time moved from the release position to the engaging 35 position. The operation continues as above described for each half turn of the shaft 4.

When thus constructed my device embodies substantially all of the advantages of a reciprocating pump. The several impellers 40 operate substantially as pistons and may be moved as slowly as desired to secure the desired discharge of fluid. My device also secures practically all of the advantages of a 45 rotary pump having large clear water passages wholly free from valves or other impediments common in all reciprocating pumps. It may also be operated substantially as rapidly as desired, as there are no 50 valves to seat, and no columns of water which must be stopped and started with each change of movement of the piston.

Obviously the mechanism herein described 55 may be employed as a very efficient water motor without material alterations, but where elastic fluid, such as steam, air or gas is to be employed to operate the device, suitable cut-off mechanism may be provided to increase the economy of its operation.

60 Having thus described my improvement it is obvious that various immaterial modifications may be made in my device without departing from the spirit of my invention, hence I do not wish to be understood as

limiting myself to the exact form or construction shown.

What I claim as new and desire to secure by Letters Patent is:

1. In a device of the kind described, a stationary cylindrical casing, a shaft extending longitudinally of said casing and a plurality of blades each independently and rotatably mounted upon said shaft and extending to the wall of said casing, in combination with means operated by the movements of said shaft for controlling the relative position of said blades and producing a variable movement between them.

2. In a device of the kind described, a stationary cylindrical casing, a rotatable shaft extending longitudinally of said casing and a plurality of blades each independently and rotatably mounted upon said shaft and filling the space between the shaft and the wall of the casing, in combination with means operated by the movements of said shaft for controlling the relative position of said blades and producing a variable movement between them.

3. In a device of the kind described, a stationary cylindrical casing, a shaft extending longitudinally of said casing and a plurality of radial blades each independently and rotatably mounted upon said shaft and extending to the wall of said casing, in combination with means positively connected to said shaft for controlling the relative position of said blades and producing a variable movement between them.

4. In a device of the kind described, a stationary cylindrical casing, a rotatable shaft extending longitudinally of, and centrally positioned in said casing and a plurality of blades each independently and loosely mounted upon said shaft and extending to the wall of said casing, in combination with means positively connected to said shaft for controlling the relative position of said blades and producing a variable movement between them.

5. In a device of the kind described, a stationary cylindrical casing, a rotatable shaft extending longitudinally of, and centrally positioned in said casing and a plurality of radial blades each loosely and independently mounted upon said shaft and extending to the wall of said casing, in combination with means periodically engaging said blades for controlling the relative position of said blades and producing a variable movement between them.

6. In a device of the kind described, a cylindrical casing, a shaft extending longitudinally of said casing and a plurality of blades independently mounted upon said shaft and extending to the wall of said casing, in combination with means for rotating said shaft and means for locking each of said blades to

said shaft during certain parts of each rotation of the blade and to said casing during other portions of its movement.

7. In a device of the kind described, a cylindrical casing, a shaft extending longitudinally of said casing and a plurality of blades each loosely and independently mounted upon said shaft and extending to said casing, in combination with means for rotating said shaft and means for locking each of said blades to said shaft during certain parts of each rotation of the blade and to said casing during other portions of its movement.

15. 8. In a device of the kind described, a cylindrical casing, a shaft extending longitudinally of said casing and a plurality of blades independently mounted upon said shaft and extending to the wall of said casing, in combination with means upon the shaft for locking each of said blades to the shaft during certain portions of each rotation of the blade, and means upon the casing for locking each plate to the casing during other portions of its movement.

9. In a device of the kind described, a cylindrical casing, a shaft extending longitudinally of said casing and a plurality of blades independently mounted upon said shaft and extending to the wall of said casing, in combination with means upon the shaft for locking each of said blades to the shaft during certain portions of each rotation of the blade and means upon the casing controlled by the movements of the shaft for locking each blade to the casing during certain portions of its movement.

10. In a device of the kind described, a cylindrical casing, a shaft extending longitudinally of said casing and a plurality of blades mounted upon said shaft and extending to the wall of said casing, in combination with means upon the shaft for moving said blades a part of a rotation and separate means for moving said blades another part of a rotation.

11. In a device of the kind described, a cylindrical casing, a shaft extending longitudinally of said casing and a plurality of blades mounted upon said shaft and extending to the wall of said casing, in combination with means upon the shaft for moving said blades a part of a rotation and separate means mounted upon the casing for moving said blades another part of a rotation.

12. In a device of the kind described, a cylindrical casing, a shaft extending longitudinally of said casing and a plurality of single independent blades mounted upon said shaft and extending to the wall of said casing, in combination with means rigidly mounted upon the shaft for engaging each blade and controlling the same a part of a rotation releasing said blade at a predeter-

mined point and engaging the next preceding blade and means for moving each disengaged blade to the point of reengagement.

13. In a device of the kind described, a cylindrical casing, a shaft extending longitudinally of said casing and a plurality of blades mounted upon said shaft and extending to the wall of said casing, in combination with means mounted upon the shaft for engaging a plurality of said blades and moving each blade for a part of a rotation releasing each blade at a predetermined point and engaging the next preceding blade, and separate means for moving each blade to complete its rotation.

14. In a device of the kind described, a cylindrical casing, a shaft extending longitudinally of said casing and a plurality of blades mounted upon said shaft and extending to the wall of said casing, in combination with means upon the shaft for successively engaging said blades and moving each blade a part of a rotation, and means upon the casing for engaging each blade as it is released from the shaft and moving the same to complete its rotation.

15. In a device of the kind described, a cylindrical casing, a shaft extending longitudinally of said casing and a plurality of blades mounted upon said shaft and extending to the wall of said casing, in combination with means upon the shaft for successively engaging the blades and moving each blade for a part of a rotation and means upon the casing for engaging each blade as it is released from the shaft and moving the same into position to be again engaged by the means upon the shaft.

16. In a device of the kind described, a cylindrical casing, a shaft extending longitudinally of said casing and a plurality of blades mounted upon said shaft and extending to the wall of said casing, in combination with automatic mechanism mounted upon said shaft adapted to successively engage said blades and move each blade a part of a rotation, means upon the casing for controlling the engagement and disengagement of said mechanism and separate means for moving each blade a part of each rotation.

17. In a device of the kind described, a cylindrical casing, a shaft extending longitudinally of said casing and a plurality of blades mounted upon said shaft and extending to the wall of said casing, in combination with a pair of drivers one at each end of said casing rigidly mounted upon said shaft and automatic mechanism mounted upon each driver adapted to successively engage said blades and move each blade a part of a rotation, means upon the casing for controlling the engagement and disengagement of said mechanism and separate means for moving each blade a part of each rotation.

18. In a device of the kind described, a cylindrical casing, a shaft extending longitudinally of said casing and a plurality of blades mounted upon said shaft and extending to the wall of said casing, in combination with a pair of drivers rigidly secured to said shaft one at each end of said casing, automatic mechanism mounted upon each driver adapted to successively engage 10 said blades and move each blade a part of a rotation, means upon the casing for controlling the engagement and disengagement of said mechanism and separate means positioned intermediate said drivers for moving 15 each blade a part of each rotation.

19. In a device of the kind described, a cylindrical casing, a shaft extending longitudinally of said casing and a plurality of blades mounted upon said shaft and extending to the wall of said casing, in combination with a pair of drivers rigidly mounted upon said shaft one at each end of said casing, automatic mechanism mounted upon each driver adapted to successively 20 engage said blades and move each blade a part of a rotation, means upon the casing for controlling the engagement and disengagement of said mechanism, and separate means positioned intermediate said drivers 25 and controlled by the movements of said shaft for engaging said blades and moving the same a part of a rotation as soon as disengaged from said drivers.

20. In a device of the kind described, a cylindrical casing, a shaft extending longitudinally of said casing and a plurality of blades mounted upon said shaft and extending to the wall of said casing, in combination with means for rotating said shaft 30 and means upon the shaft for moving said blades a part of a rotation, a screw-threaded member upon said casing, means upon each blade adapted to coöperate with said member to control the movement of said blade 35 during part of a rotation, and means for rotating said threaded member.

21. In a device of the kind described, a cylindrical casing, a shaft extending longitudinally of said casing and a plurality of blades mounted upon said shaft and extending to the wall of said casing, in combination with means for rotating said shaft and means upon the shaft for moving said blades a part of a rotation, a screw-threaded 40 member upon said casing with its axis positioned at substantially right angles to the center line of said casing, means upon each blade adapted to coöperate with said threaded member to control the movement of the 45 blade during a part of a rotation and means for rotating said member.

22. In a device of the kind described, a cylindrical casing, a shaft extending longitudinally of said casing and a plurality of

blades mounted upon said shaft and extending to the wall of said casing, in combination with means for rotating said shaft and means upon the shaft for moving said blades a part of a rotation, a screw-threaded member upon said casing, and a roller rotatably mounted upon each blade adapted to coöperate with said threaded member to control the movement of said blade during part of each rotation, and means for rotating said threaded member. 75

23. In a device of the kind described, a cylindrical casing, a shaft extending longitudinally of said casing and a plurality of blades mounted upon said shaft and extending to the wall of said casing, in combination with means for rotating said shaft and means upon the shaft for moving said blades a part of a rotation, a screw-threaded member upon said casing and means upon each blade adapted to coöperate with said threaded member to temporarily control the movement of said blades, and means connected to said shaft for rotating said threaded member. 80

24. In a device of the kind described, a cylindrical casing, a shaft extending longitudinally of said casing and a plurality of blades mounted upon said shaft and extending to the wall of said casing, in combination with means for rotating said shaft and means for moving said blades a part of a rotation, a screw-threaded member upon said casing with its axis positioned at substantially right angles to the center line of said casing, a roller rotatably mounted upon each blade adapted to coöperate with said threaded member to momentarily control the movement of said blade, and means connected to said shaft for rotating said threaded member. 90

25. In a device of the kind described, a cylindrical casing, a shaft extending longitudinally of said casing and a plurality of blades mounted upon said shaft and extending to the wall of said casing, in combination with means upon the shaft for locking said blades to the shaft during certain portions of each rotation of the shaft, a screw-threaded member upon said casing and means upon each blade adapted to coöperate with said threaded member to temporarily control the movement of said blade, and means for rotating said threaded member. 100

26. In a device of the kind described, a cylindrical casing, a shaft extending longitudinally of said casing and a plurality of blades mounted upon said shaft and extending to the wall of said casing, in combination with means upon the shaft for locking said blades to the shaft during certain portions of each rotation of the shaft, a screw-threaded member upon said casing and means upon each blade adapted to co- 110 115 120 125

operate with said threaded member to temporarily control the movement of said blade, and means connected to said shaft for rotating said threaded member.

5 27. In a device of the kind described, a cylindrical casing, a shaft extending longitudinally of said casing and a plurality of blades mounted upon said shaft and extending to the wall of said casing, in combination with means upon the shaft for successively engaging the blades and moving each blade a part of a rotation, a screw-threaded member upon said casing, and means upon each blade adapted to coöperate 10 with said threaded member as the blade is released from said shaft and control the movement of the blade, and means for rotating said threaded member.

20 28. In a device of the kind described, a cylindrical casing, a shaft extending longitudinally of said casing and a plurality of blades mounted upon said shaft and extending to the wall of said casing, in combination with means upon the shaft for successively engaging the blades and moving each blade a part of a rotation, a screw-threaded member upon said casing with its axis positioned at substantially right angles of the central line of said casing and means upon 25 each blade adapted to coöperate with said threaded member as soon as said blade is released from said shaft to control the movement of said blade, and means for rotating said threaded member.

30 29. In a device of the kind described, a cylindrical casing, a shaft extending longitudinally of said casing and a plurality of blades mounted upon said shaft and extending to the wall of said casing, in combination 35 with means upon the shaft for successively engaging the blades and moving each blade a part of a rotation, a screw-threaded member upon said casing with its axis positioned at substantially right angles to the center line of said casing and a roller rotatably mounted upon each blade adapted to coöperate with said threaded member as soon as the blade is released from said shaft to control the movement of said blade, and means connected to said shaft for rotating 40 said threaded member.

45 30. In a device of the kind described, a cylindrical casing, a shaft extending longitudinally of said casing and a plurality of blades mounted upon said shaft and extending to the wall of said casing, in combination 50 with automatic mechanism mounted upon said shaft adapted to successively engage the blades and move each blade a part of a rotation and means upon the casing for controlling the engagement and disengagement of said mechanism, a screw-threaded member upon said casing, and means upon each blade adapted to coöperate with said

threaded member to control the movement 65 of said blade and means for rotating said threaded member.

31. In a device of the kind described, a cylindrical casing, a shaft extending longitudinally of said casing and a plurality of 70 blades mounted upon said shaft and extending to the wall of said casing, in combination with automatic mechanism mounted upon said shaft adapted to successively engage said blades and move each blade independently a part of a rotation, means upon the casing for controlling the engagement and disengagement of said mechanism and a screw-threaded member upon the casing with its axis positioned at substantially 75 right angles to the center line of said casing, and means upon each blade adapted to coöperate with said threaded member to periodically control the movement of said blade, and means for rotating said threaded member.

32. In a device of the kind described, a cylindrical casing, a shaft extending longitudinally of said casing and a plurality of 80 blades mounted upon said shaft and extending to the wall of said casing, in combination with automatic mechanism mounted upon said shaft adapted to successively engage said blades and move each blade a part of a rotation, means upon the casing for controlling the engagement and disengagement of said mechanism, a screw-threaded member upon the casing and a roller rotatably mounted upon each blade adapted to coöperate with said threaded member to periodically control the movement of said blade, and means for rotating said threaded member.

33. In a device of the kind described, a cylindrical casing, a shaft extending longitudinally of said casing and a plurality of 85 blades mounted upon said shaft and extending to the wall of said casing, in combination with automatic mechanism mounted upon said shaft adapted to successively engage said blades and move each blade a part of a rotation, means upon the casing for controlling the engagement and disengagement of said mechanism, a screw-threaded member upon said casing, and means upon each blade adapted to coöperate with said threaded member to periodically control the movement of said blade, and means connected to said shaft for rotating said threaded member.

34. In a device of the kind described, a cylindrical casing, a shaft extending longitudinally of said casing and a plurality of blades mounted upon said shaft and extending to the wall of said casing, in combination 100 with automatic mechanism mounted upon said shaft adapted to successively engage said blades and move each blade a part of a rotation, means upon the casing for controlling the engagement and disengagement of said mechanism, a screw-threaded member upon said casing, and means upon each blade adapted to coöperate with said threaded member to periodically control the movement of said blade, and means connected to said shaft for rotating said threaded member.

part of a rotation, means upon the casing for controlling the engagement and disengagement of said mechanism and a screw-threaded member upon said casing with its 5 axis positioned at substantially right angles to the center line of said casing, and means upon each blade adapted to coöperate with said threaded member to control the movements of said blade, and means connected to 10 said shaft for rotating said threaded member.

35. In a device of the kind described, a cylindrical casing, a shaft extending longitudinally of said casing and a plurality of 15 blades mounted upon said shaft and extending to the wall of said casing, in combination with automatic mechanism mounted upon said shaft adapted to successively engage said blades and move each blade a part 20 of a rotation, means upon the casing for controlling the engagement and disengagement of said mechanism and a screw-threaded member upon said casing with its axis positioned at substantially right angles to the 25 center line of said casing and a roller rotatably mounted upon each blade adapted to coöperate with said threaded member to control the movement of said blade and means for rotating said threaded member.

30 36. In a device of the kind described, a cylindrical casing, a shaft extending longitudinally of said casing and a plurality of 35 blades mounted upon said shaft and extending to the wall of said casing, in combination with automatic mechanism mounted upon 40 said shaft adapted to successively engage said blades and move each blade a part of a rotation, means upon the casing for controlling the engagement and disengagement 45 of said mechanism and a screw-threaded member and a roller rotatably mounted upon each blade adapted to coöperate with said threaded member to control the movement of said blade, and means connected to said shaft for rotating said threaded member.

37. In a device of the kind described, a cylindrical casing, a shaft extending longitudinally of said casing and a plurality of 50 blades mounted upon said shaft and extending to the wall of said casing, in combination with automatic mechanism mounted upon said shaft adapted to successively engage said blades and move each blade a part of a rotation, means upon the casing for controlling the engagement and disengagement 55 of said mechanism and a screw-threaded member upon said casing with its axis positioned at substantially right angles to the center line of said casing, a roller rotatably mounted upon each blade adapted to coöperate with 60 said threaded member to control the movement of said blade, and means connected to said shaft for rotating said threaded member.

38. In a device of the kind described, a 65 cylindrical casing, a shaft extending longitudinally of said casing and a plurality of blades mounted upon said shaft and extending to the wall of said casing, in combination with a pair of drivers rigidly mounted 70 upon said shaft one at each end of said casing, automatic mechanism mounted upon each driver adapted to successively engage said blades and move each blade a part of each rotation, means upon the casing for 75 controlling the engagement and disengagement of said mechanism and a screw-threaded member mounted upon said casing and means upon each blade adapted to coöperate with said screw-threaded member to temporarily 80 control the movement of said blade, and means for rotating said threaded member.

39. In a device of the kind described, a cylindrical casing, a shaft extending longitudinally of said casing and a plurality of 85 blades mounted upon said shaft and extending to the wall of said casing, in combination with a pair of drivers rigidly secured to said shaft one at each end of said casing, 90 automatic mechanism mounted upon each driver adapted to successively engage said blades and move each blade a part of a rotation, means upon the casing for controlling the engagement and disengagement of said 95 mechanism and a screw-threaded member upon said casing positioned intermediate said drivers, and means upon each blade adapted to coöperate with said threaded member to control the movement of said 100 blade temporarily, and means for rotating said threaded member.

40. In a device of the kind described, a cylindrical casing, a shaft extending longitudinally of said casing and a plurality of 105 blades mounted upon said shaft and extending to the wall of said casing, in combination with a pair of drivers rigidly mounted upon said shaft, one at each end of said casing, automatic mechanism mounted upon 110 each driver adapted to successively engage said blades and move each blade a part of a rotation, means upon the casing for controlling the engagement and disengagement of said mechanism and a screw-threaded 115 member upon said casing positioned intermediate said drivers and extending substantially at right angles to the center line of said casing and a roller rotatably mounted upon each blade adapted to coöperate with 120 said threaded member to periodically control the movement of said blade and means connected to said shaft for rotating said threaded member.

41. In a device of the kind described, a 125 cylindrical casing, a shaft extending longitudinally of said casing and a plurality of blades mounted upon said shaft and extend-

ing to the wall of said casing, in combination with a pair of drivers rigidly mounted upon said shaft one at each end of said casing, automatic mechanism mounted upon each driver adapted to successively engage said blades and move each blade a part of a rotation, means upon the casing for controlling the engagement and disengagement of said mechanism and a screw-threaded member upon said casing positioned intermediate said drivers and controlled by the movement

of said shaft, and means upon each blade adapted to coöperate with said threaded member to temporarily control the movement of said blade.

15

In testimony whereof, I have hereunto signed my name in the presence of two subscribing witnesses.

CHARLES H. BIRCH.

Witnesses:

BURTON U. HILLS,
BLANCHE CHALMERS.
